MEANS FOR FORMING MIXTURES OF FLUIDS AND DELIVERING MEASURED QUANTITIES OF THESE MIXTURES

L. Le Roy-Meersmans, Berchem, Belgium

Application September 29, 1937, Serial No. 166,429. In Belgium October 2, 1936

6 Claims. (Cl. 277—18)

The invention relates to the formation of mixtures of fluids and the delivery of these mixtures and concerns particularly the means to be used to ensure such formation and delivery.

5 The main purpose of the invention is to render these means more efficient and better suited to meet the requirements, particularly so as to insure the mixing of at least two fluids in any desired proportion and then the delivery of this 10 mixture in any desired quantities.

To this end, the invention consists in the parts and the arrangements and combinations of parts hereinafter described and claimed.

In the accompanying drawings—

15 Fig. 1 is a cross sectional view of a mixing cock made in accordance with the invention;

Fig. 2 is a part longitudinal section through this cock, made approximately along the line 2—2 of Fig. 1;

20 Figs. 3 and 4 show in axial section and in cross section along 4—4 of Fig. 3, respectively, a mixing cock provided with an adjusting device for the delivery of the resulting fluid and a distributing arrangement of this fluid to several distinct 25 branches;

Figs. 5 and 6 show in axial longitudinal section and in cross section along 6—6 of Fig. 5, respectively, an alternative construction of mixing cock including a device for adjusting the delivery of the resulting fluid;

30 Figs. 7, 8 and 9 show in axial longitudinal section and in cross sections along 8—8 and 9—9 of Fig. 7, respectively, an alternative arrangement for another application, Fig. 9 showing the 35 valve operating member in a position at right angles to that of the Figs. 7 and 8.

Referring to Figures 1 and 2, 1 and 2 designate 40 couplings adapted to be connected to pipes for supplying the two fluids to be mixed together, as for example cold and hot water pipes indicated by the references 3 and 4 respectively.

45 For each of the pipes 3 and 4, there is provided an obturating member adapted to be moved for adjusting the sectional area of the associated pipe, these obturating members being of any desired type but with advantage of the type comprising a valve opening against the pressure of the fluid and further preferably restored on its seat by the action of a resilient member.

50 In the example, valves 5 and 6 have been provided, cooperating with the seats 7 and 8 respectively, which seats are retained in position by the engagement of the couplings 1 and 2 in the body 9 of the cock, the valves 5 and 6 being mounted 55 on rods 10 and 11 provided with heads 12 and

13 on which rest springs 14, the heads 12 and 13 being engaged within guides 15 of the body of the cock.

The seats 7 and 8 and the guides 15 are provided with passages 16 for the liquids to be mixed. 5

Within the body 9 of the cock there is formed a chamber 17 accommodating an operating member for the valves 5 and 6, this operating member being such and adapted to execute such movements that by one of these movements it 10 actuates one of the valves, for example the valve 6, conveniently in a progressive manner; by another movement it opens the valve 5 while allowing the valve 6 to close, and by yet another movement it allows the valve 5 to close without 15 simultaneous action on the valve 6.

To this end, in the example illustrated, there is provided a cam shaped member 18, mounted in the chamber 17 so as to rotate and oscillate in this chamber on an axle 19 suitably pivoted 20 in the body 9 of the cock.

As illustrated, the cam 18 is provided with two bosses A and B, the central lines OA and OB of which form between them an angle the value of which depends on the relative positions of the 25 heads 12 and 13 and which, in the example, differs from 180° while the heads 12 and 13 are located at the ends of one diameter.

By imparting a circular movement to the cam 18, for example in the clockwise direction, the 30 boss 21 engages the head 12 and moves the valve 6 away from its seat until a maximum opening position of this valve has been reached, the inclined portion of the boss 22 being then about to engage the head 13. 35

By continued rotation of the cam in the same direction, the boss 21 having passed the centre of the head 12, releases progressively the valve 6 which then returns on its seat, while the boss 22 moves progressively the valve 5 away from its 40 seat to a point of maximum opening.

At this moment, the head 12 has been released by the boss 21 and the valve 6 is again applied upon its seat.

The rotating movement of the cam being yet 45 continued, the inclined portion of the boss 22 then allows the valve 5 to return on its seat.

During this latter period of movement, no contact has taken place between the cam and the head 12 so that the valve 6 remains in its closed 50 position.

From the above will be seen that the fluid passing through the valve 6 may be admitted alone in the chamber 17; that by progressive closing of this valve and progressive opening of the valve 5 55

the fluids passing through the valves 6 and 5 respectively will be admitted into the chamber 17 in variable quantities, decreasing for one fluid and increasing for the other fluid, so that any desired mixture may be formed, and that the complete closing of the valve 6 and the opening of the valve 5 correspond to the admission in the chamber 17 of the fluid passing through this valve.

In the foregoing, it has been assumed that the 10 cam 18 is moved in the clockwise direction, but it is obvious that a similar operation of the valves is obtained by a movement of the cam 18 in the opposite direction. Moreover, to perform the described cycle of operation, the angular 15 movement of the cam does not exceed a portion of a turn, so that within the 360° of a turn, two or more sectors are available in each of which the movement of the cam provides, in the one and the other directions, a complete cycle of operations. The cam may naturally be provided with 20 more than two bosses such as 21 or 22.

It enters also within the limits of the invention to provide for more than two supplies of fluids having different characteristics and to arrange the cam 18 so as to obtain the desired actions on the valves controlling these supplies to form the desired mixtures of these fluids.

With reference to Fig. 2, the resulting fluid occupying the chamber 17 is carried towards any 30 external apparatus adapted for using this fluid by means of the hollow trunnion 19 of the operating cam 18, the fluid flowing through suitable openings 23 and 24 of the hub 25 and said trunnion, respectively.

35 It has been pointed out in the foregoing that within the 360° of possible angular movement of the cam two or more sectors may be found in each of which the desired cycle of operations may be performed.

40 According to the invention, advantage is taken of this possibility to ensure the distribution of the resulting fluid to each of a series of external branches.

To this end, the mixing device is associated 45 with a distributing device, the operation of which is so related to that of the mixing device that for the movements of the cam in each of the sectors corresponding to an operating cycle, the distributor occupies a position ensuring the communication of the chamber 17 with the desired 50 external branch.

In the arrangement of the Figures 3 and 4, in which, by way of example, the resulting fluid may be distributed to two external branches, in 55 the extension of the discharge hollow trunnion 19, there is provided another hollow trunnion 29 having a side opening or passage 38 which, for suitable positions of the trunnion 29, enables the fluid to enter one of the chambers 31 or 32, the 60 chamber 31 having an extension 33 provided with a coupling 34 and the chamber 32 being provided with a nozzle 35.

The inner space of the trunnion 29 is divided by means of a partition 36 into two chambers 37 and 38 communicating through an opening 39. This opening 39 is fitted with a valve 40 the tail 41 of which is connected to a movable part 42 of the operating handle 28 for the trunnion 29 and the cam 18, the position of said movable part 70 being adjustable relatively to the fixed part 43 for example through the intermediary of a threaded connection 44.

It follows that the valve 40 may be operated so as to move it away from or towards the opening 39 so as to open or close said opening in order

to adjust the delivery of the resulting fluid, and that this delivery adjustment may be ensured in any desired position of the cam 18 and trunnion 29, that is for any desired composition of the resulting fluid and for each of the distribution 5 pipes, i. e. extension 33 and coupling 34 or nozzle 35.

Thus by the operation of a single member one may obtain, the adjustment of the composition 10 of the resulting fluid, the adjustment of the delivery of this fluid and a desired direction of the distribution, observing that when modifications occur in the delivery of the resulting fluid, the composition of the latter is in no way modified, and that the resulting fluid may as well be distributed to more than two different branches that is a number of branches equal to the number of the sectors of the chamber 17 which each corresponds to a complete cycle of operations, as pointed out in the foregoing.

20 It is to be understood that the described arrangement of the valve 40 and of its operating drive is by way of example only and that similar or equivalent arrangements may be used in lieu thereof.

25 In the arrangement according to Figures 5 and 6 which relate to an alternative construction, the resulting fluid is distributed to a single branch 45, but with a delivery controlled by means of a valve 46 actuated in a manner similar to that of the valve 40 of the Figures 3 and 4.

30 In this arrangement, the pipes supplying the fluids to be mixed are located more or less close together and due to this the valves 5 and 6 and their rods 11 and 10 are arranged in a V formation, while the outline of the cam 18 becomes approximately an oval. In other respects this arrangement and its operation are in accordance with the description given in reference to the preceding Figures 1, 2, 3 and 4.

35 The described mixing devices may be used for widely different purposes; however they have been specially devised for fitting baths and similar equipments.

40 In this connection and in accordance with the Figures 7 to 9 the mixing and distributing device has been combined with a syringe-injector by means of which one may obtain, at will, either the injection through a nozzle with the desired delivery of a resulting fluid of a predetermined 45 composition or the flow of said fluid through the same nozzle under a comparatively small pressure head for syringing purpose.

45 The arrangement of these figures includes a mixing device for example in accordance with the Figures 1 and 2. The distributing hollow trunnion 19 of this mixing device is provided with an extension in the form of a hollow trunnion 29 fitted with an obturating member 40 operated by a handle 28 similar to the handle of the device illustrated in the Figures 3 and 4 or 5 and 6, for controlling the delivery of the resulting fluid at the nozzle or coupling 45 to which is connected the injection pipe (not shown.)

50 Further there is provided a container 46 communicating through a passage 47 with the chamber 48 accommodating the trunnion 29 having a passage 49 so formed therein that when said passage is placed into communication with the passage 47, both the supply pipes of the fluids to 55 be mixed are closed by their respective valves.

55 The operation is as follows:

60 When the injection is desired, the trunnion 29 is moved in such a position that no communication between the passage 49 and the passage 70

47 will be possible through the whole of the corresponding sector of the operation of the mixing device. For example, said passage 48 is moved in a sector corresponding to the positions illustrated in the Figures 8 and 9.

5 The resulting fluid then flows directly, through the hollow trunnion 29 and the valve 40, towards the nozzle or coupling 45 and the injection pipe connected therewith, the desired composition of 10 the resulting fluid being ensured by suitably rotating the cam 18 in the considered sector and the delivery of the fluid being adjusted by suitably actuating the valve 40 by means of the part 42 of the handle 28.

15 Should syringing be desired, the container 46 is first filled with the aid of a flexible injection pipe (not shown), by executing the same operations as in the case of the injection proper; then by suitably rotating the hollow trunnion 29, the 20 passage 49 is made to coincide with the passage 47, while the valves 5 and 6 are returned to their closed positions due to the corresponding rotation of the cam 18, and, by then opening the valve 40 by suitable actuation of the member 42 25 of the handle 28, the liquid of the container 46 is allowed to flow towards the nozzle 45 and the pipe connected therewith.

To ensure the coincidence between the passages 49 and 47 one of the movements of the cam 30 18 corresponding to a sector in which both the obturating members 5 and 6 are closed may be used or alternatively, the cam 18 may be shaped so that both obturating members are closed during a more extended period of movement of the 35 trunnion 29 and cam 18 than that ensuring the desired coincidence.

Fig. 9 shows a cam 18 so arranged, this cam being hollowed at C so that the coincidence of the passages 47 and 49 is obtained only after a 40 comparatively extended period of movement of the trunnion 29, of about 30°, in order to ensure a good thickness of the closure of the pipe 47.

Although certain embodiments and certain applications only have been particularly described, 45 it is to be understood that the invention is not limited thereto but that it includes the alternative and equivalent constructions as well as the other applications.

I claim:

50 1. A valve device for forming predetermined mixtures of fluids and delivering said mixtures in predetermined quantities comprising in combination, a valve body, pipes supplying fluids of different characteristics united to said body, valves mounted in said body for controlling the delivery of said pipes, a rotatable cam-shaped member for controlling the positions of said valves, said body having a mixing chamber, means forming a delivery outlet, a rotatable trunnion, 55 said trunnion connected to said cam-shaped member and provided with a passage for the fluid flowing from the mixing chamber to the delivery outlet, means for adjusting the flow of the fluid through the passage of the trunnion, 60 a handle movable in a single plane and connected to the trunnion to rotate the latter and the cam-shaped members, and means movable on said handle for actuating the control means of the fluid passage of the trunnion.

70 2. A valve device for forming predetermined mixtures of fluids and delivering said mixtures in predetermined quantities comprising in combination, a valve body, pipes supplying fluids of different characteristics united to said body, valves mounted in said body for controlling the

delivery of said pipes, means rotatable in the body for controlling the position of said valves, said body having a mixing chamber, means providing a delivery outlet, a rotatable trunnion provided with a longitudinal passage for the fluid flowing from the mixing chamber to the delivery outlet, a valve mounted in said passage for adjusting the flow of the fluid therethrough, a handle movable in a single plane and connected to the trunnion to rotate the latter, parts of 10 the handle connected to said valve in said passage and said parts being movable longitudinally to said handle for adjusting the position of the valve.

3. A valve device for forming predetermined mixtures of fluids and delivering said mixtures in predetermined quantities comprising in combination, a valve body, pipes supplying fluids of different characteristics united to said body, valves mounted in said body for controlling the 20 delivery of said pipes, a rotatable cam-shaped member for controlling the positions of said valves, said body having a mixing chamber, means providing a delivery outlet, a rotatable trunnion, said trunnion being operatively connected to said cam-shaped member, a partitioned 25 passage through said trunnion for the fluid flowing from said mixing chamber towards said outlet, said partition having a valve opening therein and a valve associated to said opening, a handle 30 for rotating the trunnion, and means axially movable on said handle for operating the valve.

4. A valve device for forming predetermined mixtures of fluids and delivering said mixtures in predetermined quantities comprising in combination, a valve body, pipes supplying fluids of different characteristics united to said body, valves mounted in said body for controlling the delivery of said pipes, a rotatable cam-shaped member for controlling the positions of said 40 valves, said body having a mixing chamber, means providing a delivery outlet, a rotatable trunnion operatively connected to said cam-shaped member, a partitioned passage through said trunnion for the fluid flowing from said 45 mixing chamber towards said outlet, said partition having an opening therein, a handle movable in a single plane and operatively connected to said trunnion to rotate the same, a valve member mounted in said handle and cooperating with 50 the opening of the partition for controlling said opening, and rotatable parts on said handle to adjust the position of the valve member relatively to the opening.

5. A valve device for forming predetermined mixtures of fluids and delivering said mixtures in predetermined quantities comprising in combination, a valve body, pipes supplying fluids of different characteristics united to said body, said body having a mixing chamber therein, means 60 for controlling the delivery of each of said pipes to said mixing chamber to form mixtures, external distributing branches, a distributing device for distributing the resulting mixtures to said branches including a hollow rotatable 65 axially motionless trunnion having a delivery outlet communicating with said mixing chamber, said trunnion being operatively connected to the control means, a handle movable in a single plane for operating the rotatable trunnion 70 whereby the formed mixtures may be delivered to a selected external branch, and means on the handle to adjust the flow of the resulting mixtures through said trunnion.

6. A valve device for forming predetermined 75

mixtures of fluids and delivering said mixtures in predetermined quantities comprising in combination, a valve body, pipes supplying fluids of different characteristics united to said body, said body having a mixing chamber therein, means for controlling the delivery of each of said pipes to said mixing chamber, external distributing branches, a distributing device including a hollow rotatable trunnion axially motionless having a delivery outlet adapted to register with said external branches and a passage for placing

said outlet in communication with said mixing chamber, a valve controlling said passage, said trunnion being operatively connected to the control means, a handle movable in a single plane, for operating the rotatable trunnion whereby mixtures may be formed and delivered to a selected external branch, and means movable on said handle to actuate the valve in the trunnion passage to adjust the flow of the mixtures therein. 5
